UNITED STATES PATENT OFFICE

126,870

DESIGN FOR A RADIO

Semjon Krasnikov, Chicago, Ill.

Application April 6, 1940, Serial No. 91,530

Term of patent 3½ years

To all whom it may concern:

Be it known that I, Semjon Krasnikov, a citizen of Estonia, residing in Chicago, in the county of Cook and State of Illinois, have invented a new, original, and ornamental Design for Radio, of which the following is a specification, reference being had to the accompanying drawing, forming part thereof.

Fig. 1 is a front elevational view of radio showing my new design;

Fig. 2 is a side elevational view thereof;

Fig. 3 is a top plan view thereof;

Fig. 4 is a somewhat enlarged front elevational view of the radio showing half of the upper part only;

Fig. 5 is a vertical mid-sectional view of the portion illustrated in Fig. 4.

I claim:

The ornamental design for a radio, substantially as shown.

SEMJON KRASNIKOV.
